ADJUSTABLE SHAFT STOP

Jay E. Barth, Pitman, N. J., assignor to Radio Corporation of America, a corporation of Delaware

Application September 30, 1947, Serial No. 777,075

7 Claims. (Cl. 74—52.6)

1

This invention relates to adjustable stops for electrical control shafts and the like and, while not limited thereto, will be described as applied to the solution of a problem which arises in connection with the installation and operation of phonographs of the type used by phonograph-record dealers in demonstrating their wares.

The maximum power output of the vacuum tube amplifiers used in modern phonographs is usually considerably greater than can be utilized in a confined space. Accordingly, in installing such a phonograph in an auditorium, show room, or record-demonstration booth, it has previously been proposed to limit the output of the amplifier by means of an adjustable "stop" on the volume control shaft. The principal trouble with such stops is that they either are inaccessible and require the use of special tools in their adjustment or that they are so obviously accessible that they invite manipulation by unauthorized persons.

Accordingly, the principal object of the present invention is to obviate the foregoing and other less apparent objections to present day adjustable shaft-stops and, more specifically, to provide a concealed, yet easily accessible stop of the general character described and one which may be adjusted by an unskilled person without the use of special tools.

Another and important object of the present invention is to provide a novel and inexpensive adjustable shaft-stop and one which may be applied to a shaft of standard form and dimensions without the use of tools and without in any way altering the shaft per se.

The invention will be described in connection with the accompanying drawing wherein:

Fig. 1 is a view in elevation of a part of a vacuum tube amplifier with the front panel of the set partly broken away to reveal the volume control shaft and an adjustable stop, within the invention, for said shaft; Fig. 2 is a side elevation, Fig. 3 is a front elevation and Fig. 4 is a rear elevation of the shaft-mounted parts of the stop shown in Fig. 1.

In Fig. 1 of the drawing there is shown a vacuum tube amplifier comprising a chassis 1 and a control panel 2; the panel being provided with spaced apertures 3 and 4 through which a tone-control shaft 5 and a volume-control shaft 6 project, respectively. These apertures 3 and 4 are normally concealed by removable control knobs, exemplified by the knob 7, on the outer end of each shaft. The volume-control shaft 6 is provided with adjustable stop 8, indicated generally

2

at 8, for adjustably limiting the output of the amplifier by limiting the range of movement of the said shaft 6.

The adjustable stop 8 of the invention, as here illustrated, comprises a stationary arm 9, struck out from the panel of the chassis 1 adjacent to the inner end of the shaft 6 and off-set from the axis of rotation of the said shaft. A helical (inner) spring 10 (see Fig. 2) is wound clockwise about the said axis and is normally biased to engage the shaft 6 so that it rotates therewith. There is a sleeve in the form of a second preferably heavier, spring 11 about the inner spring 10 and this sleeve 11 is provided adjacent to its inner end with an extending arm 12 for limiting the arc of movement of the shaft 6 by engaging the stationary arm 9. The inner spring 10 is secured to this relatively rigid sleeve 11 by wrapping the inner end of the said spring about the radial arm 12, as indicated at 13, hence the sleeve 11 normally rotates with the spring 10 and the shaft 6. There is an outwardly extending projection 14 on the outer end of the spring 10 and a corresponding projection 15 on the outer end of sleeve 11. These projections 14 and 15 terminate adjacent to the plane of the panel 2 and are accessible through the panel aperture 4.

In order to set the adjustable stop of the invention for any maximum value desired the following procedure is recommended: (a) With the amplifier turned "on," pull off the knob on the volume-control shaft 6 and turn the shaft clockwise full volume i. e. until the inner radial arm 12 on the sleeve 11 engages the stationary stop 9. (b) Press against the outer projection 15 on the heavy wire sleeve 11 as if to turn it clockwise. The eraser end of a pencil may be used, in the interest of convenience, for this purpose. (c) While maintaining this "clockwise pressure" on the projection 15 grasp the end of the shaft 6 and turn it fully counter-clockwise. The volume is, or should be now at the lowest possible for the maximum obtainable. (d) Release the pressure on the projection 15. The maximum volume obtainable is now at the low limit, as explained above. It will undoubtedly be too low for any ordinary purposes. (e) To set the stop for a higher limit of maximum volume due to the reproduction not being sufficiently loud, hold the shaft 6 (to keep the arm 12 against the stop 9) and gently press the end 14 of the light spring wire 10, through the opening in 4 the panel 2, in a counter-clockwise direction for small fraction of a revolution, in order to release the biasing

force which causes the spring to "grip" the shaft. The pressure applied to the said projection 14 should be just sufficient to permit the shaft 6 to be turned clockwise. (f) Hold the said spring-end 14 and turn the shaft 6 clockwise if necessary to achieve a louder volume. (g) When the maximum desired volume is achieved release both the projection 14 and shaft 6. (h) Replace the knob on the shaft 6.

With the operation of the adjustable stop of the invention clearly in mind it will be apparent that the sole purpose of the outer spring or sleeve 11 is to provide means (i. e. the projection 15) adjacent to the panel opening 4 for holding the inner spring 10 against the stationary stop 9 while making the counter-clockwise adjustment which is necessary to achieve a lower volume. Hence this sleeve 11 may be omitted whenever accessibility is not a major consideration. If the sleeve 11 is omitted it is then necessary to hold the inner projection 13 against the stationary arm 9 (as with the fingers of one hand) in order to permit the shaft to be turned in the counter-clockwise direction required to achieve a lower-volume setting. The omission of the sleeve 11 is deemed to be within the scope of the present invention.

In the embodiment of the invention that has been selected for purposes of illustration the sleeve 11 comprises a relatively strong, non-yieldable spring. This construction was selected because it permits the projections 12 and 15 thereon to be made integral with the sleeve and hence dispenses with the soldering or welding operations which might be necessary if the sleeve were to be constituted of sheet metal.

It will now be apparent that the present invention provides a simple inexpensive and trouble-free adjustable shaft-stop and one which may be applied to, and adjusted upon, a volume-control shaft or the like without the use of tools.

What is claimed is:

1. An adjustable stop for a shaft having an axis of rotation, said adjustable stop comprising a stationary arm mounted adjacent to said shaft and off-set from the axis of rotation thereof, a helical spring mounted about said axis and normally biased to engage said shaft for rotation therewith, an extending projection connected to said spring in register with said stationary arm, and a second projection on an end of said spring and to which a force may be applied for temporarily relieving its biasing force upon said shaft whereby to permit of relative rotary movement of said shaft with respect to said spring and thereby to alter the extent of the normal movement of said shaft about its axis by limiting the arc of movement of said extending projection with respect to said stationary arm.

2. The invention as set forth in claim 1 and wherein said stationary arm and said extending projection are mounted adjacent to one end of said helical spring and said second projection comprises the opposite end of said helical spring.

3. An adjustable stop for a shaft having an axis of rotation, said adjustable stop comprising a stationary arm offset from shaft, a helical spring mounted about said axis and normally biased to engage said shaft for rotation therewith, a sleeve secured to said spring for rotation therewith and provided on one end with an extending arm for engagement with said stationary arm, an extending projection on the other end of said spring and to which a force may be

applied in a direction counter to that of said biasing force whereby to permit of relative rotary movement of said spring and sleeve with respect to said shaft and thereby to alter the extent of the movement in one direction of said shaft for limiting the arc of movement of said extending sleeve-arm with respect to said stationary arm, and a discrete extending projection on the corresponding end of said sleeve for temporarily holding said sleeve arm against said stationary arm whereby to permit relative movement in the opposite direction of said shaft with respect to said spring and sleeve and thereby to alter the extent of said movement of said shaft by limiting the arc of movement of said sleeve arm in said opposite direction with respect to said stationary arm.

4. The invention as set forth in claim 3 and wherein said sleeve comprises a relatively rigid helical spring, and said sleeve arm and said projection thereon comprise the opposite ends of said relatively rigid helical spring.

5. The invention as set forth in claim 3 and wherein said sleeve comprises a relatively rigid helical spring, said sleeve-arm and said projection thereon comprise the opposite ends of said relatively rigid helical spring, and one end of the inner one of said helical springs is wrapped about the extending arm of said outer helical spring.

6. In a vacuum tube amplifier installation having a control panel and a volume-control shaft which extends through an aperture in said front panel, said aperture being normally concealed by a removable knob on the free-end of said shaft; an adjustable stop for limiting the arc of movement of said shaft and hence the output of said amplifier, said adjustable stop comprising a stationary arm mounted adjacent to the inner end of said shaft and off-set from the axis of rotation thereof, a helical spring mounted about said axis and normally biased to engage said shaft for rotation with said shaft, a sleeve mounted on said spring for rotation therewith and provided adjacent to its inner end with an extending arm

for limiting the arc of movement of said shaft by engagement with said stationary arm, an extending projection on the outer end of said spring and accessible through said panel opening for temporarily relieving the biasing force applied to said shaft whereby to permit of relative rotary movement, in one direction, of said shaft with respect to said spring and said sleeve and thereby to alter the extent of the movement in said direction of said shaft by limiting the arc of movement of said extending sleeve-arm with respect to said stationary arm, and a discrete extending projection on the outer end of said sleeve and accessible through said panel opening for temporarily holding said inner arm against said stationary arm whereby to permit relative movement in the opposite direction of said shaft with respect to said spring and sleeve and thereby to alter the extent of said movement of said shaft by limiting the arc of movement of said inner sleeve-arm, in said opposite direction, with respect to said stationary arm.

7. In a vacuum tube amplifier installation having a control panel and a volume-control shaft which extends through an aperture in said front panel, said aperture being normally concealed by a removable knob on the free-end of said shaft; an adjustable stop for limiting the arc of movement of said shaft and hence the output of said amplifier, said adjustable stop comprising: a stationary arm mounted adjacent to the inner end

of said shaft and off-set from the axis of rotation thereof, a helical spring wound counter-clockwise about said axis and normally biased to engage said shaft for rotation therewith, a sleeve mounted on said spring for rotation with said shaft and provided adjacent to its inner end with an extending arm for limiting the arc of movement of said shaft by engagement with said stationary arm, an extending projection on the outer end of said spring adjacent to said panel opening and to which a counter clockwise force may be applied for temporarily relieving the biasing force applied to said shaft whereby to permit of relative rotary movement, in the clockwise direction, of said shaft with respect to said spring and said sleeve and thereby to alter the extent of the movement in the clockwise direction of said shaft by limiting the arc of movement of said extending sleeve-arm with respect to said stationary arm, and a discrete extending projection on the outer end of said sleeve and accessible through said panel opening for temporarily hold-

ing said inner arm against said stationary arm whereby to permit relative counter-clockwise movement of said shaft with respect to said spring and sleeve and thereby to alter the extent of said clockwise movement of said shaft by limiting the arc of movement of said inner sleeve-arm, in the counter-clockwise direction, with respect to said stationary arm.
